UNITED STATES PATENT OFFICE.

ABRAHAM G. HAMAKER, OF EBERLY'S MILLS, PENNSYLVANIA.

IMPROVEMENT IN STEPS FOR UPRIGHT SHAFTS.

Specification forming part of Letters Patent No. 59,594, dated November 13, 1866.

To all whom it may concern:

Be it known that I, ABRAHAM G. HAMAKER, of Eberly's Mills, Cumberland county, and State of Pennsylvania, have invented an Improved Step for Spindles or Upright Shafts; and I do hereby declare the following to be an exact description thereof, reference being had to the accompanying drawings, and to the letters of reference marked thereon, making a part of this specification, in which—

Figure 1 represents a side elevation of the spindle operating upon three balls; Fig. 2, a top view of the same.

The nature of my invention consists in the arrangement and combination of a round-pointed spindle revolving upon three balls that revolve in a flanged disk as a movable step for the spindle.

A represents the square frame that supports the spindle B. C is a circular platform, to which the circular disk D is permanently attached. This disk D has a circular flange,

that forms a circular box that contains three balls, E, fitting closely, and resting upon the smooth bottom of the box. The vertical shaft or spindle B has a rounding point, that rests in the center upon the three balls E, (not between them, as friction-rollers, but upon their upper central sides,) forming a revolving step that gives an easier, steadier motion to the spindle and lessens the friction, the step or balls E revolving with the spindle.

G represents ordinary mill-burrs or a fly-wheel on a shaft.

What I claim as my invention, and desire to secure by Letters Patent, is—

The arrangement and combination of a round-pointed spindle revolving upon and with three balls as a revolving step, as herein described, and for the purposes set forth.

ABRAHAM G. HAMAKER.
